UNITED STATES PATENT OFFICE.

EDGAR J. BLOOM, OF TIFFIN, OHIO.

ACCELERATOR MECHANISM.

Application filed November 2, 1923. Serial No. 672,432.

To all whom it may concern

Be it known that I, EDGAR J. BLOOM, a citizen of the United States, residing at Tiffin, in the county of Seneca and State 5 of Ohio, have invented a new and useful Accelerator Mechanism, of which the following is a specification.

This invention relates to mechanism for use in the actuation of the accelerator of an 10 automobile or other structure utilizing an internal combustion engine, one of the objects of the invention being to eliminate the foot rest usually employed and to provide a means whereby the foot can rest comfortably 15 on the floor board at all times when operating the accelerator mechanism.

Another object is to provide a mechanism having a varying leverage or progressive action whereby during the first portion of the 20 operation the motion is comparatively slow but increases progressively under the steady pressure of the foot.

Another object is to provide mechanism of this character which can be set at any 25 angle so as to adapt it for use with any arrangement of parts located adjacent the accelerator, thereby materially reducing the cost of installation.

A further object is to reduce the number 30 of parts and provide a noiseless smooth acting structure which will not become clogged.

With the foregoing and other objects in view which will appear as the description proceeds, the invention resides in the combination and arrangement of parts and in the details of construction hereinafter described and claimed, it being understood that changes in the precise embodiment of the invention herein disclosed may be made 40 within the scope of what is claimed without departing from the spirit of the invention.

In the accompanying drawings the preferred form of the invention has been shown.

In said drawings—

45 Figure 1 is a section through a portion of the floor board of an automobile showing the present invention combined therewith, the progressive action of the lever during the depression of the ball being illustrated.

50 Fig. 2 is a bottom plan view of a portion of the lever, the ball and its housing, said lever being illustrated by broken lines in several positions to which it may be adjusted angularly.

55 Fig. 3 is a plan view of the ball and its housing.

Fig. 4 is a transverse section through a modified form of structure, the ball being shown in elevation.

Fig. 5 is a section on a line 5—5, Fig. 4. 60

Fig. 6 is a transverse section through a portion of the attachment and floor board showing a rug extending thereover.

Fig. 7 is a view partly in section and 65 partly in side elevation showing the mechanism combined with a floor plate having a integral housing.

Fig. 8 is a view partly in section and 70 partly in elevation showing another modification.

Fig. 9 is a side elevation of the flexible 75 cap which can be used for closing the upper end of the ball of the housing.

Fig. 10 is a section on a reduced scale 75 of another modified form.

Referring to the figures by characters of reference 1 designates the floor board of an automobile or other structure in which is provided an opening 2 for the reception of a housing 3 fitting snugly therein. In the 80 structure illustrated in Figs. 1 and 5 an annular flange 4 is provided at one end of the housing and is fastened to the floor board by screws 5 or the like. This housing also has an inwardly extending annular flange 6 85 at said end which constitutes a retainer for a ball 7 loosely mounted in the housing 3. This ball can be of rubber, wood, metal or any other suitable material, although in practice it has been found that rubber is usually 90 the most desirable because it is noiseless and yields under the pressure of the foot thereagainst.

The housing is provided on its outer face with a longitudinal rib 8 projecting into a 95 recess 9 formed in the wall of the opening 2 and thus acting to hold the housing against rotation within the opening. Ears 10 are extended downwardly from the housing, preferably at the lower end of the rib, and pivotally mounted on a pin 11 extending through these ears is a lever 12. One end of the lever may be provided with a longitudinal series of openings 13 whereby said lever can be connected adjustably to the accelerator. The other end of the lever is preferably extended to form a projecting nose 14 which, by moving upwardly against the wall of the housing 3, will limit the downward swinging of the lever. 105

The lever is normally extended diametrically across and in contact with the end of

the housing 3, that portion of the lever adjacent the housing being provided with oppositely extending flanges 15 providing a rest or support for the ball 7. It is to be understood that the housing can be adjusted angularly within the opening 2 so that the lever 12 can be extended at any desired angle relative to the longitudinal center of the floor board as indicated by broken lines in Fig. 2. It is only necessary to so locate the recess 9 as to receive the rib 8 when the parts are in their desired positions. This adjustment of the parts enables the lever to be extended in any direction where it will be prevented from interfering with the carburetor rod or other parts that may be adjacent thereto.

As has been illustrated in Figs. 4 and 5 the housing 16 corresponding with the housing 3 can be formed with longitudinal slots 17 and for the purpose of holding the housing spaced from the wall of the opening 18 in floor board 19 a rib 20 can be formed on the annular flange 21 so as to project into the opening 18 and thus hold the housing centered as shown. By thus forming the housing, there is no danger of dirt or other foreign substances accumulating in the housing and interfering with the operation of the ball 22.

Under some conditions, as where the floor board is made of metal as shown at 23 in Fig. 7 the housing 24 can be made integral therewith and the ears 25, which are integral with the housing, will support one end of the lever 26, on which ball 27 rests.

On some automobiles it is desirable to exert a pull through the lever of the accelerator mechanism and for this purpose the present invention can be modified as shown in Fig. 8 wherein an angular lever 28 is fulcrumed at its angle portion between the ears 29 of the housing 30, the pivot being indicated at 31. Thus ball 32 engages one arm of the lever while the other arm is provided with a series of apertures 33 for attachment to the accelerator.

As illustrated in Fig. 6 the rug 34 can be placed over the ball or, if preferred, a cap 35 formed of rubber, leather, or any other suitable flexible material can be fastened upon the housing so as to extend across the ball and conceal it and also protect it from wear and dirt.

In using the device herein described the foot of the operator will rest comfortably on the floor and by pushing downwardly the ball will be caused to thrust against the lever and thus set up a progressive action or variable leverage of the lever. This action has been clearly illustrated in Fig. 1. As therein shown, when the ball begins its thrusting action it bears against the lever at a distance from its fulcrum indicated by the radius C but as the lever moves under

the action of the ball this radius is reduced with the result that when the lever reaches the limit of its movement its point of contact with the ball is much nearer the fulcrum as shown by radius A, the distance 70 designated by line B being eliminated and the speed of movement of the lever consequently gradually increasing during the uniform movement of the ball in one direction. This arrangement of the parts gives the ball 75 and the parts operated thereby an easy action at the beginning of the thrusting action of the ball and renders the structure especially suitable for crowded traffic when a vehicle is required to move at a very low 80 speed. This speed can be quickly increased by pushing the ball to the full limit of its throw. The progressive action or variable leverage permits of greater range of ball action for slow speeds without in any way 85 hindering the full speed action.

As is well known the accelerator button is often very close to the brake pedal and in pushing the brake lever down to its limit the foot often touches the accelerator, causing the engine to race and if the clutch is not disengaged the vehicle will jump forward. This has often caused serious accidents. By using a low operating element such as the ball forming a part of this invention the accidental operation of the accelerator in the manner described is entirely eliminated as the brake pedal can be pushed far down and still be higher than the ball herein described.

Because of the low position of the ball it can be operated by any portion of the foot, thereby making it unnecessary to set the foot in a certain position in order to actuate the accelerator.

It might be added that the present improvements have been found very helpful in laying out a vehicle and locating the starter mechanism. As the actuating ball used in the present invention is very much 100 lower than the starting button, one cannot be mistaken for the other as happens in the present car installation utilizing a high accelerator and starter button as well as a high foot rest button. The present arrangement allows the starter button to be placed in a more comfortable location than heretofore.

It has often been necessary in automobile construction to locate the accelerator in the 110 floor board at such a position that it is impossible to use a straight rod on the carburetor, this being due to the particular location of certain parts of the motor directly in front of the accelerator. In such cases 115 bends are usually made in the connecting arm or rod of the accelerator and in some cases cross shafts, bell cranks, and the like are necessary to get around the engine to the carburetor. These bends, shafts, bell cranks 120

and the like have a tendency to cause harder action of the accelerator and also require more joints and produce greater wear. With the accelerator mechanism constituting the present invention the operating lever can be placed at any angle desired, as illustrated in Fig. 2 to eliminate cross shafts, bell cranks or bent rods. Consequently the cost of installation is reduced and a smoother working action is secured.

It will be obvious that by using a ball as a thrust member, several working joints are eliminated and as the ball is fitted loosely in its housing it is not subjected to material wear and consequently the structure is more lasting than heretofore.

While the improvements are especially designed for use in connection with automobiles, it will be understood that they can be employed in connection with any structure using an engine of the internal combustion type wherein an accelerator is desirable.

While a ball is preferably used and is the most advantageous means for thrusting against the lever, it is to be understood that under some circumstances a push button might be employed in the housing in lieu thereof.

If a rug or mat is extended over the accelerator ball, the same can be suitably marked to indicate the location of the ball.

Under some conditions it is desirable to provide a means whereby the accelerator can be operated by hand as is usually the case.

To meet this requirement the lever 36 can have an eye extended from its short arm as indicated in Fig. 10 and a wire cable or a rod can be attached to this eye and to the end of the rod on the steering collar in the usual way. In all other respects the structure illustrated in Fig. 10 can be the same as those disclosed in the other figures of the drawings.

What is claimed is:

1. The combination with an accelerator lever, of a housing, and a thrust member loosely mounted in the housing and supported by the lever, said member adapted to impart a varying leverage to the lever, a portion of said member projecting normally from the housing.

2. The combination with an accelerator lever, of a housing having an interior retaining flange, a thrust member loosely mounted in the housing and retained therein by the flange and lever, for imparting a varying leverage to the lever during the movement of the member in one direction, said member normally projecting from one end of the housing.

3. The combination with a housing, of an accelerator lever fulcrumed thereon, a thrust member within the housing and supported by the lever for imparting a varying leverage to the lever during the movement of the

member in one direction, and a flexible closure extending over the housing and thrust member.

4. The combination with a housing open at its ends and having an apertured wall, of an accelerator lever, a thrust member loosely mounted within the housing and normally supported by the lever for imparting a varying leverage thereto during the movement of the member in one direction.

5. The combination with a housing open at its ends and having an apertured wall, of an accelerator lever, a thrust member loosely mounted within the housing and normally supported by the lever for imparting a varying leverage thereto during the movement of the member in one direction, and a flexible cover extending over the housing and thrust member.

6. The combination with a housing, of an accelerator lever fulcrumed thereon, cooperating means on the housing and lever for limiting the movement of the lever away from the housing, and a thrust member loosely mounted within the housing and normally supported by the lever for imparting a varying leverage thereto during the movement of the member in one direction.

7. The combination with a housing having an interior flange at one end, said housing being open at both ends, of a lever extending across the other end of the housing, a ball loosely mounted in the housing and retained between the flange and lever.

8. The combination with an accelerator lever, of a housing and a ball loosely mounted in the housing and bearing against the lever, a portion of the ball normally projecting from the housing.

9. The combination with an accelerator lever, of a housing and a ball loosely mounted in the housing and bearing against the lever, a portion of the ball normally projecting from the housing, and a flexible cover extending over the ball and housing.

10. The combination with an accelerator lever, of a housing having openings in the wall thereof, and a push ball loosely mounted in the housing and supported by the lever, a portion of the ball normally extending from the housing.

11. The combination with an accelerator lever, of a push ball supported by the lever and means for guiding the ball to impart a progressive action to the lever during the actuation of the ball.

12. The combination with a floor board having an opening, of an angularly adjustable housing supported in the opening, an accelerator lever extending across one end of the housing and adjustable therewith, and a push ball loosely mounted in the housing and engaging the lever, said ball having a portion normally projecting from the housing.

13. The combination with a floor board having an opening therein, of an angularly adjustable housing within the opening, cooperating means upon the housing and floor board for holding the housing against rotation, an accelerator lever adjustable angularly with the housing and extending thereacross, and a push ball loosely mounted within the housing.
- 10 14. The combination with a floor board having an opening, of a housing supported within the opening and having apertures in the wall thereof, an accelerator lever extending across one end of the housing, and a push ball loosely mounted within the housing and normally engaging the lever, a portion of the ball projecting normally from the housing.
- 15 15. The combination with a floor board having an opening, of a housing extending from the floor board, an accelerator lever extending across one end of the housing, and a push ball loosely mounted in the housing and bearing against the lever, a portion 25 of the ball normally projecting from the housing.
- 20 16. The combination with a floor board having an opening, of a housing extending from the floor board, a retaining flange within one end portion of the housing, an accelerator lever extending across the other end portion of the housing, and a push ball loosely mounted in the housing between the flange and lever and extending from the 30 floor board.
- 25 17. The combination with a floor board
- having an opening, of a housing extending from the floor board, a retaining flange within one end portion of the housing, an accelerator lever extending across the other end portion of the housing, and a push ball loosely mounted in the housing between the flange and lever and extending from the 35 floor board, and a flexible cover extending over the push ball to close the housing.
- 40 18. The combination with an accelerator lever, of a housing, and means movably mounted in the housing for imparting a varying leverage to the lever during the movement of said means.
- 45 19. The combination with a housing, of an accelerator lever having oppositely extending arms, one of said arms extending across the housing, operating means movably mounted in the housing, and depressible therein to impart a varying leverage to the lever, means on one arm of the lever for engagement with an actuating device, the other arm of the lever constituting means 50 for connection to an accelerator.
- 55 20. The combination with an accelerator lever, of a push member supported by the lever and means for guiding said member to impart a varying leverage to the lever during the actuation of the member.
- 60 In testimony that I claim the foregoing as my own, I have hereto affixed my signature in the presence of two witnesses.
